UNITED STATES PATENT OFFICE.

ROBERT WANDEL, OF REUTLINGEN, GERMANY.

KNOTTER OR STRAINER FOR PAPER MANUFACTURE.

1,105,227.

Specification of Letters Patent. Patented July 28, 1914.

Application filed January 2, 1914. Serial No. 810,061.

To all whom it may concern:

Be it known that I, ROBERT WANDEL, subject of the King of Wurttemberg, residing at Reutlingen, Germany, have invented certain new and useful Improvements in Knotters or Strainers for Paper Manufacture, of which the following is a specification.

This invention relates to rotatable knotters or strainers employed in the manufacture of paper, card board, cellulose or the like of the type in which the sieve or sorting drum is carried by swinging levers capable of being reciprocated vertically at their free ends so as to impart a jerking or shaking motion to the drum. Hitherto it has been usual to reciprocate the free ends of the levers by means of cams or ratchet wheels acting on the free ends of the levers but this arrangement is too noisy in operation. It has therefore been sought to insure quieter running of the machine by positively connecting the free ends of the levers to rotatable eccentrics, but this arrangement has the drawback that the oscillatory motion imparted to the levers is too subdued, not being energetic enough to effect efficient straining of the material. Moreover, it has usually been almost impossible to enable the throw of the eccentric to be varied.

One object of the present invention is to provide for efficient shaking of the drum while enabling the shaking motion to be varied according to requirements, at the same time providing for quiet running of the machine.

A further object of the present invention is to provide an adjustable bearing for the drum so as to enable the stepwise rotation of the drum to be varied according to the material under treatment as it has been found that excessive wear of the bearings takes place, unless the latter are made adjustable. Moreover, with non-adjustable bearings the stepwise rotation of the drum could not be regulated to suit the different materials and if rotated too rapidly too much material was thrown off into the knot collecting trough, whereas if rotated too slowly the straining or sorting action was defective as the perforated drum rapidly became choked, thus resulting in unequal weight in the finished paper or tearing of the wet paper strip.

According to the present invention the foregoing disadvantages are obviated by

connecting the free end of the levers carrying the drum to the eccentrics in such a manner that the latter are capable of freely reciprocating vertically when the levers are at a corresponding height, while jerkily but noiselessly raising the levers and thus effecting energetic shaking of the drum. The free downward movement of the levers is limited in the usual manner by an adjustable strap. Moreover, the leather or like bearing surfaces supporting the drum are capable of adjustment by means of adjustable segments or by means of an adjustable steel or other flexible band beneath the leather bearing surface.

In order that the invention may be more clearly understood reference is made to the accompanying drawings showing two embodiments of the invention by way of example.

Figure 1 is an end view of the knotter or strainer and Fig. 2 a detail end view drawn to an enlarged scale. Fig. 3 is an end view of the knotter or strainer having adjustable bearing surfaces and Fig. 4 is a fragmentary plan thereof.

The sorting drum *b* rests within a trough *a* upon swinging levers *c* which are rotatably mounted at one end upon pivot pins *d*, the other end *e* of the lever being free to move upwardly and downwardly. The free end *e* of the levers is surrounded by a strap *h* having a screwed stem *o* adjustable by means of an internally screwed hand wheel or nut *f* upon the arm or support *p*, a rubber cushion *g* or the like being preferably interposed between the support *p* and nut *f*.

Mounted upon a rotatable shaft *i* beneath each swinging lever *c* is an eccentric *k*, the strap *l* of which is connected to a slotted bar or rod *m* fitting beneath the end *e* of the lever *c*. A transverse pin *r* on the lever *c* fits in a slot *s* in the eccentric rod *m* thus insuring the relative position of the parts *e* and *m*.

In Figs. 1 and 2 of the drawings the lever *c* is shown resting in the strap *h*, while the eccentric *k* is in its lowermost dead point position. On the rotation of the eccentric *k* the rod *m* strikes the end *e* of the lever *c* and swings the latter upwardly. The drum *b* moves therewith and since the lever swings about the pivot pins *d* the drum will be raised at the righthand side a greater

amount than at the lefthand side and thus also rotates about the pivot pins *d*, particularly when the bearing surfaces between the lever *c* and the journals *n* of the drum *b* 5 are constructed of leather or the like.

When the eccentric *k* has reached its uppermost dead point the downward movement of the lever *c* commences and may, if desired, be accelerated by means of a spring

10 in the usual manner. The drum *b*, however, does not move down simultaneously with the lever *c*, but will continue its upward movement for a short time owing to its momentum. The friction at the bearing surfaces will thus be diminished and the drum *b* 15 will continue to rotate until it again rests upon the bearing surfaces of the levers *c*. It has been found that the shaft *i* can be driven at a speed of 300 to 600 revolutions 20 per minute. In this manner the drum *b* is set in stepwise rotation about its axis.

In order to make the friction at the bearings independent of the wear and enable the angular velocity of the drum to be varied 25 according to the material under treatment, the leather or like bearing surfaces on the levers *c* are capable of adjustment and as shown in Figs. 3 and 4 may be adjusted by means of studs *v*. The bearings may, for 30 example, consist of segments inserted between the bearing surface of the lever *c* and the leather lining, these segments being capable of adjustment toward the journals *n* of the drum by means of the studs *v*. If 35 desired, however, a steel or like elastic band may be provided beneath the leather lining, this band being adjustable by means of set screws or studs. The flexible band or the adjustable segments will be preferably fitted 40 in grooves in the bearing.

I claim:

1. The improved knotter or strainer comprising a sorting drum, swinging levers supporting said drum, a member supporting the 45 free end of each of said levers, an eccentric and a member connected to said eccentric

and adapted to raise the free end of each of said levers but to fall independently thereof.

2. The improved knotter or strainer comprising a sorting drum, swinging levers supporting said drum, a member supporting the free end of each of said levers, an eccentric and a forked member actuated by said eccentric and embracing the free end of each 50 of said levers. 55

3. The improved knotter or strainer comprising a sorting drum, swinging levers supporting said drum, adjustable straps supporting the free ends of said levers, a shaft, eccentrics on said shaft, forked members slotted at right angles to the fork thereof, straps around said eccentrics, and connected to said forked members, and transverse pins in the free ends of said levers engaging the 60 slots in said forked members. 65

4. In a knotter or strainer for paper and like pulp, a sorting drum, swinging levers supporting and adapted to reciprocate said drum, bearings on said levers for said drum, friction linings between said bearings and 70 drum, and means for adjusting said linings toward the drum.

5. In a knotter or strainer for paper and like pulp, a sorting drum, swinging levers supporting and adapted to reciprocate said 75 drum, bearings on said levers for said drum, friction linings between said bearings and drum, and adjustable segments between said bearings and linings.

6. In a knotter or strainer for paper and 80 like pulp, a sorting drum, swinging levers supporting and adapted to reciprocate said drum, bearings on said levers for said drum, friction linings between said bearings and drum, and adjustable flexible bands between 85 said bearings and linings.

In testimony whereof I affix my signature in presence of two witnesses.

ROBERT WANDEL.
